SIMPLIFIED NONPLUGGING PUMP WATER
CLOSET

Kenneth G. Shook, Marble Rock, Iowa

Application April 8, 1947, Serial No. 740,067

1. Claim. (Cl. 4—77)

1

This invention relates to improvements in non-plugging pump water closets.

An object of the invention is to provide an improved non-plugging pump water closet especially adapted for marine use in boats wherein all portions of the closet will provide direct or straight passages for the waste when the water closet is operated, thereby doing away with sharp angles which might cause plugging or stoppage of the pump mechanism connected with the water closet.

Another object of the invention is to provide an improved non-plugging pump water closet for marine use including a horizontal cylinder having a piston operatively mounted therein connected with a piston rod and associated levers and hand operating lever, together with a water inlet supply pump having its discharge connected with the rim of the bowl which is supported upon one end of said horizontal cylinder, and said water inlet supply pump being operated simultaneously with said piston by means of a link connected with the said hand operating lever.

A further object of the invention is to provide an improved non-plugging pump water closet in which all of the valves may be easily reached for inspection or replacement, and said water closet being constructed of interconnected portions being free of angle bends to provide a non-plugging operation over a long period of use.

Another object of the invention is to provide an improved non-plugging pump water closet which will be highly efficient in operation, and relatively inexpensive to manufacture and produce.

Other objects will appear as the description proceeds.

In the accompanying drawings which form a part of this application.

Figure 1 is a front elevation of the improved non-plugging pump water closet;

Figure 2 is a side elevation of the improved non-plugging pump water closet;

Figure 3 is a sectional view taken on the line 3—3 of Figure 2;

Figure 4 is a sectional view taken on the line 4—4 of Figure 1;

Figure 5 is a sectional view taken on the line 5—5 of Figure 1, and

Figure 6 is a perspective view of the outlet check valve disposable between the bowl of a water closet and the upwardly extending flanged collar at one end of the horizontal operating cylinder.

Like characters of reference are used through-

2

out the following specification and the accompanying drawings to designate corresponding parts.

In carrying out the invention, there is provided an improved non-plugging pump water closet having a horizontal operating cylinder 1 supported upon the spaced integrally formed depending legs 2 and 3 for supporting the water closet elevated above the surface 4 upon which it will be supported.

One end of the cylinder 1 will be open, and will be formed with a peripheral flange 5 having spaced threaded bolt receiving openings 6 extending therethrough. A circular closure disk or plate 7 will be formed with similar spaced alignable bolt receiving openings 8, and will be removably secured upon the open end of the cylinder 1 by means of the bolts 9 which are threaded through the aligned openings 6 and 8.

The opposite end of the cylinder 1 is closed by the head 10 which is formed with a centrally disposed bearing boss 11, said head and boss being centrally and longitudinally apertured to slidably receive the piston rod 12 whose threaded inner end extends through the cupped head 13 of the piston 14, being secured by means of the nut 15 threaded upon the threaded end of the said piston rod. A gland 16 and packing nut 17 will be disposed within the bearing boss 11 about the piston rod 12.

A pair of spaced upwardly angled bracket arms 18 are formed upon the end closure head pin, and are provided with aligned apertures through their outer ends to receive the cross pin 19 upon which the bell crank piston rod actuating lever 18 is pivotally supported, having its lower end connected by means of the cross pin 19 with the fork 20 secured to the outer end of said piston rod 12.

An upwardly extending vertical standard 21 is attached to the side of the cylinder 1, as by welding, and is apertured at its upper end to support the cross pin 22, which in turn supports the forked inner end 23 of the actuating arm 24. A handle 25 is secured to the outer end of the actuating arm 24, and a connecting rod 26 is connected at its upper end intermediate the ends of the arm 24, and is connected at its lower end to the upper end of the bell crank lever 18, whereby a reciprocating upward and downward movement of the same will cause the piston 14 to move back and forth in the horizontal cylinder 1 for operating the water closet.

A vertical valve casing or cylinder 27 will be supported by the web 28 at the end of the cylinder

1 adjacent its closed end, and supports the valve 28 and connected rod or stem 29 for reciprocating movement therein. The rod or stem 29 extends through the lower end of the valve cylinder 26 and is packed by the gland 30. A bore 72 is formed through the web 27 between the valve cylinder 26 and the cylinder 1 so as to allow water to pass from the valve cylinder 26 to the cylinder 1.

A pump operating arm 31 is pivotally supported upon the pin 32 attached to the leg 3, and a foot treadle 33 is disposed upon the outer end of said arm 31. The lower end of the piston rod 29 is forked at 34 to overlie the arm 31 and is secured thereto by the cross pin 35 which extends through said forked portion 34 and through the arm 31. A coil spring 36 will be disposed within the valve cylinder 26 about the rod or stem 29, and will lie beneath the valve 28 for normally holding the same in its uppermost position.

A water inlet pipe 37 will be connected between the side wall of the valve cylinder 26 and the side of the boat (not shown) at the point below the water line. An outlet pipe 38 will be connected with the annular flange 39 formed at the top of the toilet bowl 40.

The toilet bowl 40 is provided with the usual cover 41 which is hinged at 42 at the rear end thereof.

The lower end of the toilet bowl 40 is reduced to provide the cylindrical portion 43 which terminates in the laterally extending annular flange 44, and the inwardly extending annular flange 45 providing the restricted outlet 46 for the bowl.

An annular seat 47 is formed below the inwardly extending annular flange 45, and supports the circular disk 48 in which the downwardly operating flap or check valve 49 is hinged, being attached to the flexible or resilient metal spring strap 50, which is also attached to the disk 48. The disk 48 will seat in the annular seat 47 and will also seat upon the upper surface of the annular flange 51 formed about the upper end of the bowl supporting collar 52 formed integrally with the horizontal cylinder 1 on its upper side and adjacent its open end.

The openings 53 will be formed through the disk 48 to receive the screw bolts 54 for securing the same within the annular seat 47 in the annular flange 45.

Openings 55 and 56 will be formed respectively through the laterally extending annular flange 44 and through the annular flange 51 for alignment with each other, and to receive the securing bolts 57 for holding the toilet bowl 40 upon the annular flange 51 formed about the upper end of the bowl supporting collar 52 which is formed integrally with the horizontal cylinder 1.

An offset outlet pipe 58 will be secured to the outlet opening 59 formed through the side wall of the cylinder 1 directly below the connection from the toilet bowl 40, and an outwardly opening one way flap or check valve 60 will be secured between said pipe 58 and said opening 59, and likewise a second outwardly opening one way flap or check valve 61 will be secured between the flange 62 on the outer end of the pipe 58 and the flange 63 about the adjacent inner end of the discharge pipe 64 which extends to and through the side of the boat (not shown) and below the water line. Bolts 65 will extend through the flanges 62 and 63 to form a tight joint between the pipes 58 and 64.

In operation, the valve 28 and valve cylinder 26 serve as a controlling valve. When the pedal 33 is depressed, it lowers the valve 28 in the valve

cylinder 26 exposing the water intake and lets water in through the pipe 37 into the valve cylinder 26 and through the bore 72, into the cylinder 1. The valve 28 is lowered by pressing down on the pedal 33 and when in its lowered position, the action of the piston 14 moving inwardly towards the plate 7 pumps water from pipe 37 into the cylinder 1 through said bore or opening 72. After the water is drawn into the cylinder 1 by the piston 14, the return stroke of piston 14 will drive the water out of the cylinder 1 through the bore 72 into the valve cylinder 26 and through the pipe 38 into the rim of the bowl 4, flushing the contents which will first move from the toilet bowl 40 into the cylinder 1, and will then be discharged past the flap or check valves 60 and 61 and out through the pipes 58 and 64 into the water outside the boat (not shown) and below the water line. The portion of the bore or opening 72 is such that it will be open and unobstructed at all times regardless of the position of the piston 28.

From the foregoing description, it will be seen that there has been devised and provided a simplified non-plugging pump water closet which will be highly efficient in operation, and relatively inexpensive to manufacture and produce.

While the preferred embodiment of the instant invention has been illustrated and described, it will be understood that it is not intended to limit the scope of the invention thereto, as many minor changes in the detail of construction may be resorted to without departure from the spirit of the invention.

Having thus described my invention what I claim as new and desire to secure by Letters Patent of the United States is:

A non-plugging pump water closet comprising a horizontal cylinder, a piston and piston rod reciprocatingly slidable in said cylinder, means to actuate said piston, a toilet bowl connected to said horizontal cylinder, a web on said cylinder, a valve housing carried by said web, an inlet port in said valve housing, a lateral port connecting said valve housing and cylinder and disposed in said web, a valve reciprocatingly mounted in said housing and normally closing said inlet and lateral ports, means to operate said valve, an outlet pipe connected between said valve housing and said toilet bowl, a check valve between said toilet bowl and cylinder, discharge means for said water closet, a vertical standard on the cylinder adjacent its closed end, said first-named means including a manually operable arm pivotally supported on said standard, a link depending therefrom and a bellcrank lever connected between said link and piston rod.
